CLAIM

The ornamental design for a optical fiber splice re-entry tool, as shown and described.

DESCRIPTION

FIG. 1 is a perspective view of the optical fiber splice re-entry tool;

FIG. 2 is a front elevational view thereof;

FIG. 3 is a right side elevational view thereof;

FIG. 4 is a rear elevational view thereof;

FIG. 5 is a left side elevational view thereof; and,

FIG. 6 is a bottom plan view thereof.

FIG. 1

*FIG. 2**FIG. 3*FIG. 4

FIG. 5

FIG. 6
